[57] CLAIM

The ornamental design for a fluorescent lamp adapter base, as shown and described.

DESCRIPTION

FIG. 1 is a top front perspective view of a fluorescent lamp adapter base showing the new design, the fluorescent lamp being shown in broken lines for illustrative purposes only;

FIG. 2 is a top plan view thereof;

FIG. 3 is a front elevational view thereof, the rear and sides being identical.

FIG. 4 is a bottom plan view thereof.

FIG. 1

FIG. 2

FIG. 3

FIG. 4
